UNITED STATES PATENT OFFICE.

OSIAS M. GOTTESMAN AND IRVIN ROSENFELD, OF NEW YORK, N. Y., ASSIGNEES TO
HARVEY INSTRUMENT CO., INC., A CORPORATION OF NEW YORK.

THERMOMETER ATTACHMENT.

Application filed January 16, 1924. Serial No. 686,539.

- Our invention relates to improvements in holders for returning the mercury in clinical thermometers, and more particularly has reference to a whirling or centrifugal device which may be in the form of an attachment to be applied to the thermometer case for whirling the thermometer so as to return the mercury by centrifugal force without undue exertion on the part of the patient.
- 5 In the accompanying drawings, I have illustrated in Fig. 1, a suitable form of thermometer holder or case partly broken away, showing an application of my attachment in folded position. Fig. 2 is a similar view at 10 right angles showing the attachment extended in position for whirling the case containing the thermometer. Fig. 3 is a detailed view in perspective of the clip for detachably applying the attachment, and Fig. 15 20 25 30 35 40 45 50 55 60 65 70 75 80 85 90 95 100 105 4 is a cross-sectional detail illustrating the application of the balls in the spirals.
- 4 indicates the case provided with a cap 5, all of which somewhat resembles a fountain pen, the projection 6 being rectangular, 25 hexagonal, or octagonal, as may be desired to prevent the holder from rolling when placed on a smooth surface. 7 indicates a conventional form of clinical thermometer such as may be carried in a case of the kind described.
- 30 35 40 45 50 55 60 65 70 75 80 85 90 95 100 105 8 indicates a resilient clip pivotally secured to the stud 9 between which is also secured or may be formed with the clip 8, the resilient strip 10, 11 having end depressions such as 12, 13 adapted to seat within the annular recesses 14, 15 in the sockets or tubes 16, 17 respectively. 18, 19 indicate rods, the adjacent ends of which penetrate the stud 9, and the same are provided with spirals such as 20, 21 of opposite pitch. 22, 23 indicate balls seated in the spirals and retained in holes or depressions in the sleeves 17, 16 as shown.
- By pressing the two handles or sockets 16, 17 in the direction of each other, the case 4, 5 will thereby be whirled in one direction and by withdrawing the finger pieces will be whirled in the opposite direction, thereby causing the mercury in the thermometer 7 to return to the lower end of the thermometer, and after being used, the finger pieces and their rods may be folded parallel with the case as shown in Fig. 1, thus rendering the same adaptable for carrying in the pocket when desired.
- There are several reasons for pivoting the attachment off centre. In the first place, the mercury end of the thermometer stands in the long end of the case, and the mercury is therefore returned to that end where the centrifugal force acts more fully than it does at the short end. Then again, the cap of the case being shorter, the short end of the attachment is folded so as to extend at the top while the long end conforms more particularly to the long end of the holder. In order to compensate for the difference in length of the stroke of the short end compared with the stroke of the long end of the attachment, the spirals on the short end are closer together, thereby bringing the finger pieces or sockets together and apart simultaneously, notwithstanding the difference in length of stroke.
- Of course it will be understood that various modifications may be made in the construction and arrangement of parts without departing from the spirit of the invention as claimed.
- We claim:
1. A centrifugal device comprising a holder and a stud pivoted thereto, a pair of opposed spiral members secured to said stud, and sockets engaging the spirals of said members adapted when brought together and apart to rotate said holder, the spirals on one side being closer together and opposed to the spirals on the other side of said stud.
  2. A centrifugal device comprising a holder and a stud pivoted thereto, spiral members secured to said stud, and sockets engaging the spirals of said members adapted when brought together and apart to rotate said holder, the spirals on one side being closer together and opposed to the spirals on the other side of said stud, and in combination therewith a resilient clip for retaining said spiral members and sockets in axial alignment with said holder.
  3. A restoring device for a thermometer case comprising means for attaching said thermometer to said restoring device, a member having spiraled portion at opposite ends pivoted to said means at a point between said spirals, and finger engaging

sockets engaging said spirals, whereby when said sockets are made to approach or recede, said attaching means is whirled in one direction and then in another, said attaching means comprising a spring clip.

4. A restoring device for a thermometer case comprising means for attaching said thermometer to said restoring device, a member having spiraled portions at opposite ends pivoted to said means at a point between said spirals, and finger engaging sockets engaging said spirals, whereby when

15
said sockets are made to approach or recede, said attaching means is whirled in one direction and then in another, said attaching means comprising a spring clip, and in combination therewith a resilient holder for retaining said spirals and sockets parallel with the axis of said clip.
